UNITED STATES PATENT OFFICE.

JOHN HUGH MEANS, OF MAYVILLE, WISCONSIN.

COOLING SYSTEM FOR BLAST-FURNACES

1,102,281.

Specification of Letters Patent. Patented July 7, 1914.

Application filed June 21, 1912. Serial No. 705,057.

To all whom it may concern:

Be it known that I, JOHN H. MEANS, a citizen of the United States, residing at Mayville, in the county of Dodge and State 5 of Wisconsin, have invented certain new and useful Improvements in Cooling Systems for Blast-Furnaces; and I do hereby declare the following to be a full, clear, and exact description and specification of the invention, 10 such as will enable others skilled in the art to which it appertains to make and use the same.

My invention relates to a means for the thorough cooling, protection and preservation 15 of the brick work contained in the inwalls of blast furnaces by means of a plurality or series of water pipes arranged, placed and joined in the manner hereinafter indicated; and the objects of my improvement or 20 device are,—first, to provide the thorough cooling and preservation of the brick work contained in the inwalls of blast furnaces; second, to secure all the advantages heretofore attained by the so-called external 25 method of cooling blast furnace walls without incurring the disadvantages of spray pipes which clog, causing hot spots on the furnace shell, without the collection of sediment on shell, which decreases the cooling 30 effect and without splashing or slopping of water which is attendant upon surface cooling,—third, to prevent and avoid troublesome leaks caused by the loosening of joints in cooling pipes now employed,—fourth, to 35 prevent and avoid the corrugation of the brick work which now occurs in horizontal plate cooled blast furnace inwalls,—fifth, to secure any or all of the advantages of the present so-called thin walled blast furnaces 40 without incurring their disadvantages, sixth, to retain a very large proportion of the latent heat contained in the furnace wall and thereby materially reduce the coke consumption 45 of the furnace. I secure and attain these objects and advantages by the construction shown in the accompanying drawing which represents a vertical section of a blast furnace provided with this improvement.

50 A represents a blast furnace which may be of any desired construction and provided with any desired appliances.

As this invention is not confined in its application to any particular construction of 55 blast furnace, and is equally applicable to either an old or new furnace, a detailed

description of the different parts of the furnace illustrated in the drawing is not deemed necessary.

B represents the bosh of the furnace—C 60 the top—and D the inwall, extending upwardly from the mantle E, which is carried on the columns F, to the top C.

G represents the cooling pipes each furnished with inlet and outlet branches H and 65 I respectively. The number and length of pipes employed depend on the size of furnace. The pipes G are arranged vertically in the furnace wall, and may extend from any desired point above the mantle E, to 70 any desired height, but as the furnace tapers toward the top it is desirable to use a number of sets of pipes, as shown in the drawing with a less number of pipes in the upper set or sets, thereby keeping the distance between the pipes more uniform. Each pipe G is embedded in the wall of the furnace and located 12 inches (more or less) from the inner surface of the furnace wall.

The inlet and outlet branches H and I are 75 formed integrally with the pipes G by bending them or are welded thereto so as to avoid fittings or joints which are liable to become loose and leaky and occasion trouble inside the furnace wall. Outside of the inwall D 80 and the jacket or shell J surrounding it, the inlet branches H of the several cooling pipes G are connected by elbows K and pipes L with an annular water supply pipe M surrounding the furnace above and adjacent to 85 the mantle E. The inlet branches H or the pipes L connecting them with the supply pipe M are provided with valves N for controlling the supply of water to the several cooling pipes G separately, so that if any of 90 said pipes is broken or defective it may be cut out without affecting the operation of the others and without materially impairing the protection afforded by the system as a whole to the inwall D. The outlet branches 95 I of the several cooling pipes G are connected by elbows O with overflow or discharge pipes P which extend downwardly outside of the shell J and open at their lower ends into an open annular trough Q surrounding the 100 furnace, thus affording means in constant and clear view for determining whether water is flowing freely through the several cooling pipes G.

The construction of the several single 110 cooling pipes G integrally with inlet and outlet branches H and I extending di-

rectly outward through the inwall D as herein shown and described, not only facilitates laying the wall in which they are embedded, but also avoids pipe joints or fittings which are liable to become loose and leak within the wall. The arrangement of the pipes and their connections and the provision of the several single cooling pipes G with separate supply and discharge connections at their lower and upper ends respectively, as shown, also avoids pockets or bends in which sediment is liable to lodge and clog them and causes an upward flow of water through them, keeping them completely filled and serving more effectively to keep them clear of dirt and sediment.

I am aware that the idea of cooling by means of naked water pipes embedded in a furnace bosh and open hearth port arches, is old; and that various methods and means have been employed for cooling the bosh and crucibles of blast furnaces, as well as the arch in open hearth ports and heating furnaces, but so far as I am aware a cooling system consisting of a series of single, vertically disposed water pipes embedded in the inwall of a blast furnace and having jointless branches extending directly outward through the furnace wall and each having an independent water supply connection with its lower branch and an open and visible discharge connection with its upper branch is new.

It is evident that many slight changes in the construction and relative arrangement of parts, might be resorted to without involving a departure from this invention, and hence I would have it understood that I do not restrict myself to the exact construction and arrangement of parts shown and described.

Having now described my invention, what I claim as new and desire to secure by Letters Patent is—

1. A cooling system for blast furnaces comprising a series of single vertically disposed jointless water cooled pipes embedded at intervals in the inwall above the bosh of a furnace and having at their lower and upper

ends respectively inlet and outlet branches formed integrally therewith and extending directly outward therefrom through said inwall, the inlet branches being provided with separate valve controlled water supply connections, and the outlet branches being provided with separate discharge connections, all outside of said inwall.

2. A cooling system for blast furnaces comprising a series of vertically disposed water pipes embedded at intervals within and around the inwall of a furnace and each having inlet and outlet branches at its lower and upper ends respectively extending directly outward through the inwall, an annular water supply pipe connected with the inlet branches of the several cooling pipes outside of the furnace, an open trough encircling the furnace, and discharge pipes leading downwardly from the outlet branches outside the furnace and opening into said trough.

3. A cooling system for blast furnaces comprising single vertically disposed cooling pipes embedded at intervals within and around the inwall of a furnace, a water supply pipe having separate valve controlled connections with the lower ends of the several cooling pipes outside the furnace, an open trough surrounding the furnace, and discharge connections leading from the upper ends of the cooling pipes and opening in clear view into said trough.

4. A cooling system for blast furnaces comprising a water supply pipe surrounding the furnace, a number of series arranged one above another of separate vertically disposed cooling pipes embedded at intervals within and around the inwall of a furnace above the bosh and each having a valve controlled connection at its lower end with said supply pipe and a discharge connection at its upper end.

JOHN HUGH MEANS.
